UNITED STATES PATENT OFFICE.

WILLIAM J. LUTTON, OF PATERSON, NEW JERSEY.

SHUTTLE-BOX-OPERATING MECHANISM FOR LOOMS.

SPECIFICATION forming part of Letters Patent No. 440,487, dated November 11, 1890.

Application filed March 28, 1890 Serial No., 345,661. (No model.)

To all whom it may concern:

Be it known that I, WILLIAM J. LUTTON, of Paterson, in the county of Passaic and State of New Jersey, have invented a certain new and useful Improvement in Shuttle-Box-Operating Mechanisms for Looms, of which the following is a specification.

This invention relates to multiplier mechanisms for looms and is adapted to be employed in connection with a pattern-chain.

In carrying out my invention I employ, in connection therewith, a drop-shuttle-box mechanism operated by vibrating levers controlled by a pattern-chain through intermediate gear of well-known form and arrangement. (See, for example, patent to Knowles, No. 221,237.) My reference to such well-known mechanism will therefore be brief, as it is herein shown only for the purpose of making clear the structure, arrangement, and operation of the multiplier mechanism.

In the accompanying drawings, Figure 1 represents a portion of a loom in end elevation having my invention applied thereto. Fig. 2 represents an enlarged view of the parts embodying my invention, as shown in Fig. 1. Fig. 3 is a section taken on the line $x-x$ of Fig. 2, the vibrator-levers being omitted, and certain parts being shown in elevation. Fig. 4 is a view in detail of a chain-wheel and portion of chain thereon. Fig. 5 is a view in detail of the multiplier-controlling mechanism. Fig. 6 is a view in detail of the compound lever. Fig. 7 is a view in detail of a stop employed in connection with the controlling mechanism. Fig. 8 shows a modified form of certain parts.

A represents the frame of the loom; a , the reciprocating support for the drop-boxes; a' , the lay; B, the flexible connection between the drop-box support and the compound lever; $b b'$, the compound lever; C, the vibrator-levers; c , the connecting-arms between the crank-gears on the vibrator-levers and the compound lever; D, the chain-supporting wheels; d , the chain-actuating spur-wheel; d' , a drive-wheel secured on the main shaft E; e , an intermediate gear-wheel, meshing with the drive-wheel d' and having a pinion e' and a mutilated gear E' secured to rotate therewith, the pinion e' meshing with the

chain-actuating wheel d and having a cam e^2 for actuating the dog e^3 for engaging and releasing the vibrator-levers; F, a mutilated gear-wheel driven from the main shaft by means of an intermediate gear-wheel f , intermeshing with the drive-wheel d' and with a wheel F' , fixed on a shaft to rotate with the wheel F; and f' one of a set of mutilated gear-wheels mounted on the vibrator-lever and having attached eccentrically thereto one end of the connecting-arm c for operating its section of the compound lever.

The parts to which I have thus briefly alluded are well known in the art, combined and arranged substantially as shown, and it is not thought necessary to give a detailed statement of their operation, as the same is well known to those skilled in the art, my present invention pertaining to certain means for controlling the operation of certain of the above-named parts, in order to multiply the effect of a set of rollers on the pattern-chain, thereby saving length of chain.

G represents a stud or axle secured in the loom-frame, and provided with a sleeve G, to which the sprocket-wheels D, which support the pattern-chain, are secured, and on which the chain-actuating spur-wheel d is loosely mounted. One side of the wheel d is provided with an annular series of pockets d^2 , located at equal distances apart to receive the head of a spring-actuated key, as will appear farther on. A wheel or plate H is fixed to the sleeve g in proximity to the wheel d , and carries a socket h , projecting from its side, in which a key h' here shown in the form of a plunger, is seated, in such a position as to admit of its head h^2 entering one of the pockets d^2 as the wheel d is rotated on the sleeve. The key h' is held normally under spring-tension by means of a spring h^3 , tending to force it into engagement with the wheel d . For the purpose of locking it in released adjustment, I provide its outer end with a handle h^4 , having set in its end dowel-pins h^5 , adapted to enter sockets h^6 in the end of the wall of the socket h . By simply drawing the key back from the wheel d until the pins h^5 are released from their sockets, and then giving it a partial turn, it may be held in released adjustment until again set in position.

The wheel H is also provided with a handle I for convenience in rotating it, and with ratchet-notches *i* on its periphery, the purpose of which will hereinafter appear.

- 5 A controlling wheel or plate K of peculiar form is fixed on the stud G in front of the wheel H, and is provided with an annular series of inclined faced ledges *k* along the edge of its periphery, the said ledges being separated by intervening plain spaces *k'*, a portion of the periphery of the wheel being preferably cut away at such intervening spaces to prevent unnecessary friction between the stud L, to be hereinafter described, and the face of the wheel while the key is engaged in a pocket in the wheel *d*. The opposite side of the periphery of the said wheel is provided with a series of notches *k*² at points opposite the ledges *k*.
- 10 The handle *h*⁴ of the key *h'* has a lateral extension *h*⁷, through which a screw-stud L projects into position to engage the ledges *k* as the said key and stud are carried around by the wheel H in engagement with the actuating-wheel *d*. There is also secured to the handle *h*⁴ a stop *l*, the free end of which is so located that it will be drawn gradually into the recess *k*² as the stud L rides up the inclined face of the ledge *k*, and just as the said stud 15 passes over the abrupt end of the ledge the end of the stop will engage the wall of the recess *k*², and so prevent the wheel H from further movement in the same direction. The pattern-chain herein shown consists of sections formed by corresponding side links *W* united with a succeeding pair of side links by pivotal bars *w*, on which rollers *w'* are mounted and spaced apart in groups of the desired number by sleeves *w*².
- 20 The operation of the parts as thus far described is as follows: Suppose the wheel H to have been turned by the operator to set the pattern-chain in the desired adjustment, and the key *h'* to be engagement with the actuating-wheel *d*. As the stud L reaches one of the ledges *k* and travels along up its inclined face, it will gradually withdraw the key from engagement with the wheel *d*, and hence stop the pattern-chain at or near a predetermined 25 point to introduce the desired shuttle. The release of the key from the actuating-wheel *d* takes place, however, before the stud L clears the ledge, and in order to advance the wheel H to a position where the stud L will 30 clear the ledge and drop back into position to allow the key to again engage a pocket in the actuating-wheel *d*, and to bring the pattern-chain into proper adjustment, I provide a push-pawl in engagement with the periphery 35 of the wheel H. One form of such push-pawl is represented at M, the same being mounted on an eccentric *m* on the main shaft, with its free end resting in contact with the wheel H in position to engage one of the teeth *i* at the 40 proper time to complete the rotary movement of the wheel for the above said purposes. When such movement of the wheel H is com-

pleted, the stop *l* will engage the wall of the recess *k*², as above stated, preventing the displacement of the pattern-chain by overweight 45 in one direction, while the stud L in engagement with the abrupt end of the ledge *k* will prevent its displacement in the opposite direction. The result of such automatic stopping of the chains is to multiply the effect of a single set of rollers or bar of the chain. For example, suppose the six pockets *d* in the actuating-wheel *d* to be open and the key *h'*, seated in one of them, locking the wheel H, and hence the pattern-chain to rotate with the actuating-wheel *d*, and the stud L occupying the position which it assumed immediately after passing over one of the ledges *k*. As the key is carried along with the wheel H, the stud L will travel from the 50 abrupt face of one of the ledges *k* along the plain intervening space *k'* and up the inclined face of the next succeeding ledge *k* until the key is released from the actuating-wheel *d*. This travel corresponds to the distance 55 between two successive pockets on the actuating-wheel, in the present instance to one-sixth of its revolution, and also to the one-sixth revolution of the chain-supporting wheel, which brings a new set of rollers or 60 bar of the chain into position to give the desired movement to the vibrator-levers. The completion of the movement of the wheel H, which throws the stud L over the ledge, is accomplished as hereinbefore described. In this 65 position the pattern-chain will rest until the next succeeding pocket in the actuating-wheel *d* is brought opposite the head of the key—that is, it will rest during another sixth revolution of the wheel *d*, and the effect of 70 the set of rollers or bar of the pattern-chain upon the vibrator-levers will be double.

If every alternate pocket in the actuating-wheel *d* be filled by a suitable stopper N, it will follow from the reasons above set forth 75 that the effect of a single set of rollers or bar on the chain will be three times what it would be in a continuously-moving chain, since the key will now be held out of engagement with the actuating-wheel through a distance corresponding to two-sixths or one-third of its revolution. Again, if two of the pockets in the wheel *d* be left open (the two located at equal distances apart) and the remainder of the pockets be filled, it will follow that the 80 effect of a single set of rollers or bar of the chain will be four times what it would be with a constantly-moving chain, while if all the pockets except one be closed its effect will be seven times what it would be if the 85 chain were constantly moving.

Instead of the stop *l*, which I have described, I may employ a stop consisting of a roller O, journaled in a spring-arm *o* and adapted to seat in depressions *o'* along the periphery of 90 the wheel H, as shown in Fig. 1.

In the place of the wheel H with ratchet-teeth on its periphery and the pawl M, actuated by an eccentric upon the main shaft, I

may employ a polygonal-shaped plate H', (see Fig. 8,) and provide a spring-actuated pawl M', arranged to contact with the periphery of the said plate H', and serving, because of its spring-pressure against the periphery of the plate, to complete its movement and to hold it against forward or backward displacement.

What I claim as my invention is—

- 10 1. The combination, with a wheel or plate having a movement in unison with the pattern and a pattern-actuating wheel loosely mounted upon a suitable support in proximity to the said wheel or plate and having its axis in line with the axis of said wheel or plate, of a locking and releasing device carried by said wheel or plate and having a movement relative to the wheel or plate at predetermined intervals to lock the actuating-wheel to the said wheel or plate and release it therefrom, and an operating device with which the locking and releasing device engages during its travel with the wheel or plate, substantially as set forth.
- 15 2. The combination, with a wheel arranged to rotate with the pattern and carrying a spring-actuated key, of a pattern-actuating wheel provided with key-seats at intervals on its side for locking it to the key-carrying wheel and a controlling-plate fixed in position to engage the key and provided with a series of inclines thereon, adapted to release the key from the actuating-wheel at predetermined intervals, substantially as set forth.
- 20 3. The combination, with a wheel or plate arranged to rotate with a pattern and carrying a key, of a pattern-actuating wheel provided with key-seats at intervals thereon, means for releasing the key from the actuating-wheel,

and a device for positively rotating the key-carrying wheel or plate to complete its movement, substantially as set forth.

4. The combination, with a wheel or plate H, arranged to rotate with the pattern and a pattern-actuating wheel, of a key for locking and releasing the said wheel or plate H to or from its actuating-wheel, means for disengaging the key from the actuating-wheel at predetermined intervals, and a stop for locking the pattern against displacement, substantially as set forth.

5. The combination, with a wheel or plate arranged to rotate with the pattern and carrying a key and an actuating-wheel provided with seats for the key, of a fixed controlling-plate provided with a series of inclines in position to engage the key and release it from the actuating-wheel, the main shaft, an eccentric on the main shaft, and a pawl in engagement with the key-carrying wheel and actuated by the said eccentric to complete the movement of the wheel, substantially as set forth.

6. In combination, the pattern-actuating wheel, a key supported to move with the pattern and arranged to lock and release the pattern to and from its actuating mechanism, a controlling-plate having a series of ledges on its side in position to engage the key and a series of notches along its periphery, and a stop carried by the key and adapted to enter the notches and limit the movement of the pattern, substantially as set forth.
